W. D. WILLIAMS.
SOFT COLLAR SUPPORT.
APPLICATION FILED JAN. 24, 1918.

1,291,328.

Patented Jan. 14, 1919.

Fig. 3

Inventor:

Willis D. Williams,

By Hugh A. Wagner,
Attorney.

UNITED STATES PATENT OFFICE.

WILLIS D. WILLIAMS, OF ST. LOUIS, MISSOURI, ASSIGNOR OF ONE-HALF TO DANIEL D. CONDRON, OF PRESCOTT, ARIZONA.

SOFT-COLLAR SUPPORT.

1,291,328.

Specification of Letters Patent. Patented Jan. 14, 1919.

Application filed January 24, 1918. Serial No. 213,583.

To all whom it may concern:

Be it known that I, WILLIS D. WILLIAMS, a citizen of the United States, residing at the city of St. Louis, in the State of Missouri, have invented certain new and useful Improvements in Soft-Collar Supports, of which the following is a specification.

This invention is a reinforcement or stiffener for soft collars. A great objection to soft collars is that perspiration or wear will cause the same to bend at the top or otherwise to become crumpled. This mars their appearance.

At the present time food conservation has led to economy in the use of starch and to such an extent is this true that it has been suggested that the United States Government will ere long prohibit the use of starched, *i. e.* stiff collars, there being a similar prohibition already in force in Great Britain.

The object of the present invention is therefore to enable the wearing of soft collars by providing means that will prevent deterioration in their appearance while being worn.

In the accompanying drawings forming part of this specification, in which like numbers of reference denote like parts whenever they occur,

Figure 1 is a perspective view with the left-hand flap of the collar turned up;

Fig. 2 is a side elevation with the right-hand flap of the collar turned up, part of the front of the collar showing;

Fig. 3 is a sectional view through the collar and stiffener at the point where the back collar-button passes through the same; and

Fig. 4 is a perspective view of the stiffener.

The soft collar 1 is of the usual or any desired form or construction and is provided with the usual collar button-holes 2 and 3 and is attached to the shirt by the studs or collar-buttons 4 and 5.

The ordinary soft collar is provided with the button 6 by which the flap 7 is attached to the band 8 of the collar 1. This button 6 passes through a button-hole that is not shown in the drawings in flap 7 and is utilized in the present construction for that purpose and also for the additional one of holding one end of the stiffener 9, the said button 6 for this purpose passing through eyelet 10 in stiffener 9.

At the opposite end of stiffener 9 an eyelet 11 is provided by means of which and button 12 the said opposite end of stiffener 9 is attached to band 8. The said button 12 is sewed to band 8 but is not found in ordinary soft collars. It is provided expressly for the use of this invention in conjunction with eyelet 11 in stiffener 9.

To prevent fraying or unnecessary wear of the inside of the folded edge 13 of the collar 1 the stiffener 9 is provided with a bead or flange 14, which may be formed by bending over upon itself the upper edge of the stiffener 9, but which stiffener will preferably be formed of material that will permit of the bead 14 being formed by pressure which will make the said bead 14 integral with the body of stiffener 9. Eyelets 10 and 11 and button-hole 15 in stiffener 9 will be cut simultaneously.

Eyelets 10 and 11 must be located at precisely the right distance from the inside of edge 13 of the collar 1 so as to insure that the upper edge of bead 14 will exactly fit within the collar 1 underneath edge 13, in order to prevent the said edge from becoming bent over or crumpled. Thus it will be seen that stiffeners 9 will be manufactured of suitable sizes to fit the various sizes of collars 1.

The stiffeners 9 will preferably be made of rubber but can be made of celluloid, paper and other materials. The objection that is generally found to the use of rubber or paper collars or the like is absent when only the stiffener 9 is made of such a material while the collar 1 is itself made of ordinary cloth fabric.

It will be understood that the button 5 passes through the shirt-band 16 before it passes through the button-hole in collar 1, or through button-hole 15 in stiffener 9.

Another function and advantage arising from the bead 14 on stiffener 9 besides that described above is the fact that it equalizes the thickness of the neck-tie that passes around stiffener 9 to be tied in front. If the said bead 14 were absent, there would be an uneven empty space between the top edge of the neck-tie and the inside of the fold in collar 1 underneath edge 13.

Formed as above described, the bead 14 will present a smooth, non-cloth-wearing edge on the inside of edge 13.

Having thus described this invention, I

hereby reserve the benefit of all changes in form, arrangement, order or use of parts, as it is evident that many minor changes may be made therein without departing 5 from the spirit of this invention or the scope of the following claims.

Claims:

- 10 1. The combination with a soft fold-over collar having a flap at one end to extend into the fold at the other end, of a button within said fold to which the flap is adapted to be secured, another button on the flap-bearing end of the collar and arranged below the fold at that end, and a stiffener ar-

ranged in the fold of the collar and having eyelets adapted to receive said buttons respectively. 15

2. The combination with a soft fold-over collar, of buttons secured to the opposite end portions of the collar within the fold 20 thereof, and a stiffener having eyelets adapted to receive the said buttons respectively for retaining the stiffener in place in the fold of the collar.

In testimony whereof I hereunto affix my 25 signature.

W. D. WILLIAMS.
